(No Model.)

J. F. & G. C. BURSON.
POTTERY MACHINE.

No. 578,207.

Patented Mar. 2, 1897.

UNITED STATES PATENT OFFICE.

JOHN F. BURSON AND GEORGE C. BURSON, OF ROGERS, OHIO.

POTTERY-MACHINE.

SPECIFICATION forming part of Letters Patent No. 578,207, dated March 2, 1897.

Application filed June 22, 1896. Serial No. 596,481. (No model.)

To all whom it may concern:

Be it known that we, JOHN F. BURSON and GEORGE C. BURSON, citizens of the United States, and residents of Rogers, in the county of Columbiana and State of Ohio, have invented certain new and useful Improvements in Pottery-Machines; and we do hereby declare that the following is a full, clear, and exact description of the invention, which will enable others skilled in the art to which it appertains to make and use the same, reference being had to the accompanying drawings, which form a part of this specification.

Our invention relates to machines for molding and modeling oval, elliptical, scalloped, or other irregular forms of pottery; and its object is to provide an improved construction of the same which shall possess superior advantages with respect to efficiency in use.

20 The invention consists in the novel construction and combination of parts hereinafter fully described and claimed.

In the accompanying drawings, Figure 1 is a longitudinal sectional view of a pottery-machine constructed in accordance with our invention. Fig. 2 is a horizontal section of the same on the line *x x*, Fig. 1. Fig. 3 is a view looking from the under side of the cover for holding the mold in the jollie-head. Fig. 30 4 is a transverse sectional view of the adjustable tool-holder and tool.

In the said drawings the reference-numeral 1 designates four corner-uprights connected together by side beams 2 and end beams 3, and also by intermediate side beams 4, forming a frame or table provided with a top 5.

The numeral 7 designates a vertical shaft having at its upper end a conical or cup-shaped jollie-head 8, in which the mold to receive the clay to be worked or molded is inserted. Near the lower end the shaft is provided with a driving-pulley 9, with which is to be connected a belt (not shown) for rotating the shaft.

45 The numeral 10 designates a cog-wheel secured to said shaft, which meshes with a pinion 12, journaled to cross-bars 13, connected with the frame or table. This pinion is formed with a number of holes 14 at varying 50 distances from the center to receive a removable and replaceable crank-pin 15, to which is connected a horizontal crank 16. The rear

ends of this crank are pivoted to lugs 17, secured to a vertical bar 18. The upper and lower ends of this bar are secured to horizontal slide-bars 19, passing through brackets 20, secured to cross-bars 21. To the rear ends of these slide-bars is secured an upright 23, to which is pivoted a forwardly-extending arm 24, the front end of which is pivoted to lugs 60 25 on a movable sleeve 26. This sleeve slides or reciprocates on a pull-down 27, the rear end of which is pivoted to a bracket 28, secured to the frame or table-top.

The numeral 29 designates an adjustable 65 tool-holder consisting of a rectangular box or casing provided with a horizontal partition 30, between which and the top of the box the pull-down passes. This tool-holder can be moved back and forth on the sleeve, so as to 70 adjust it thereon, and is provided with a set-screw 31 to hold it in its adjusted position. In the bottom of the tool-holder is a longitudinal slot 32, with which engages a molding-tool 34, provided with a rectangular head 75 35, which fits in the space between said partition and the bottom of the holder and holds the tool in place. A set-screw 36, passing through the holder, serves to hold the tool in any position to which it may be adjusted, and 80 by loosening the same the tool may be moved longitudinally back and forth.

The upper edge of the jollie-head is formed with two diametric recesses 37, with which engage lugs 38 on a circular cover 39, fitting 85 on the head to hold the mold in place thereon. This cover is formed with a central oval or elliptical beveled opening corresponding with the shape of the article to be molded.

The cross-bars 13, to which the pinion is 90 journaled, are formed with semicircular registering recesses at their meeting edges, forming a circular opening to receive the journal of the pinion. The ends of these bars rest upon the short beams 40, secured to the uprights of the frame, and are held in place thereon by means of clamping-bars 41, through which and the beams 40 pass screw-bolts 42, provided with nuts 43. By loosening these nuts the bars 13 may be adjusted longitudinally to bring them nearer to or farther from the cog-wheel on the main shaft, so as to allow different-sized pinions to be used with the machine. 100

The operation is as follows: The clay to be worked is placed in a suitable mold, as usual, which in turn is placed in the cover which has been put on the jollie-head, the lugs thereof engaging with the recesses in the jollie-head to prevent the cover and mold from turning on the head or rotating independently thereof. The pull-down is then depressed, carrying the tool down into the mold in the jollie-head.

5 The shaft and jollie-head are now rotated by the pulley on the shaft, driven by any suitable motive power, causing the mold in the jollie-head to be correspondingly rotated.

10 It should be stated that only one edge of the tool operates on the clay in the mold, and as the pinion 12 is rotated by the cog-wheel the crank connected with the slide-bars will move the latter alternately back and forth, carrying with them the upright 23 and the 15 arm pivoted to the upper end thereof, causing the sleeve and tool-holder connected therewith to be correspondingly reciprocated and the tool caused to alternately approach to and recede from the center of the jollie-head and 20 thus follow the contour of the rotating mold.

25 During this operation as the pinion rotates and the crank-pin approaches the dead-center farthest from the cog-wheel the tool will be moved outward to its extreme limit and will 30 follow the longest center of the mold and will begin to recede or move toward the center of the jollie-head as the said pin passes said dead-point, and will again begin to advance as it passes the opposite dead-point, and again approaches the point farthest from the cog-wheel. If the cog-wheel and pinion rotated 35 at the same speed, this operation could not produce a perfect article, as during one-half of the rotation of the mold the tool would be 40 out of contact with the clay, so therefore the cog-wheel and pinion are so proportioned that the pinion will move two or more revolutions to one of the cog-wheel, so that as the jollie-head and mold make one rotation the tool will 45 make two or more strokes. By this means the tool always follows the contour of the mold, being at some distance therefrom at all points during its rotation.

By removing the crank-pin from the hole 50 in the pinion and placing it in another of the holes at a different distance from the axis the throw or play of the tool will be varied to form ovals or scallops more or less elongated or struck from different centers.

55 By removing the pinion and substituting therefor one of a different size irregular-shaped oval or scalloped ware may be produced.

Having thus fully described our invention, 60 what we claim is—

1. In a pottery-machine, the combination with the rotatable shaft, the jollie-head, the

cog-wheel, the differential pinion meshing therewith and the crank-pin, of the crank, the slide-bars connected therewith, the upright, 65 the arm pivoted thereto, the pivoted pull-down, the movable sleeve on said pull-down pivotally connected with said arm, the tool-holder adjustably secured thereto, formed with a slot in its bottom and provided with a horizontal portion, and the adjustable tool having a rectangular head; substantially as described.

2. In a pottery-machine, the combination with the rotatable shaft, the jollie-head, the 70 cog-wheel, the differential pinion meshing therewith formed with a number of holes at varying distances from the center and the removable and replaceable crank-pin adapted to engage therewith, of the crank, the slide-bars connected therewith, the upright, the arm pivoted thereto, the pivoted pull-down, the movable sleeve on said pull-down pivotally connected with said arm, the tool-holder adjustably secured thereto, formed with a 75 slot in its bottom and provided with a horizontal portion and the adjustable tool having a rectangular head, substantially as described.

3. In a pottery-machine, the combination with the frame, the rotatable shaft, the jollie-head, the cog-wheel secured to said shaft, the pinion meshing therewith, the adjustable cross-bars having semicircular recesses to receive the journal of said pinion, the beams on which the ends of said bars rest, the clamping-bars, the screw-bolts and the nuts, of the crank-pin on said pinion, the crank, the slide-bars, the upright, the arm pivoted thereto, the pivoted pull-down, the movable sleeve thereon, pivoted to said arm, the adjustable 90 tool-holder and the removable tool connected therewith, substantially as described.

4. In a pottery-machine, the combination with the rotatable shaft, the circular jollie-head, the removable cover having an oval 105 opening therein and provided with lugs fitting in recesses in the head, the cog-wheel located on said shaft, the differential pinion meshing therewith, and the crank-pin on said pinion, of the crank, the slide-bars connected 110 therewith, the upright, the arm pivoted thereto, the pivoted pull-down, the movable sleeve on said pull-down pivotally connected with said arm, the tool-holder adjustably secured thereto and the adjustable tool, substantially 115 as described.

In testimony that we claim the foregoing as our own we have hereunto affixed our signatures in presence of two witnesses.

JOHN F. BURSON.
GEORGE C. BURSON.
